UNITED STATES PATENT OFFICE.

ELBRIDGE R. HOLMES, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

SPACING DEVICE FOR LOOM DOBBY FINGERS.

Application filed August 24, 1926. Serial No. 131,290.

This invention relates to improvements in loom dobbies and it is the principal object of the invention to provide a dobby so constructed as to permit the use of a simplified 5 form of sheet metal dobby finger.

Dobby fingers must be spaced and kept in alignment with the pattern mechanism, this result being usually accomplished by having the outer ends of the fingers of reduced thickness to cooperate with the teeth 10 of the separating comb. It has been proposed heretofore to make dobby fingers of relatively thin sheet steel folded together to make the body of the required thickness and having the outer ends formed of a single 15 thickness to be thinner than the body to cooperate with the comb. Should a dobby finger of the usual form be made of a single piece of sheet steel a separate operation would be necessary to form the thin outer 20 end. It is an important object of my present invention to provide dobby fingers of relatively thick sheet metal shaped to fit an improved separating comb which does not 25 require that the finger ends be reduced.

It is a more detailed object of my invention to provide two types of fingers, one of which shall be slotted to receive a separating peg which will guide adjacent fingers which 30 are not slotted.

In certain picking out operations in a loom it is desirable to be able to bring all of the warp threads to the same plane, this process being known as levelling. On dobby 35 looms such as heretofore constructed, a very simple device has been provided for raising all of the dobby fingers, a condition which corresponds to lowering all of the hooks. As one or another of the knife bars moves 40 outwardly, therefore, all of the harnesses will be raised, and this operation, known as levelling up, can be accomplished very readily because of the manner in which the dobby operates. It is a still further object 45 of my invention to form the dobby fingers, in addition to the manner already described, with aligning lower edges to cooperate with the levelling device.

Dobby fingers usually cooperate with pegs 50 carried on the pattern chain and must be provided with a run on their under surfaces to receive the peg. It is a further object of my invention to form the peg engaging part of the fingers with concave runs somewhat

wider than the thickness of the sheet material of which the finger is formed and further to provide certain of the fingers with offset portions to engage the other fingers, to the end that all of the fingers may be properly aligned so that the runs will not 55 interfere with each other and will be properly located with respect to the pegs of the pattern chain.

With these and other objects in view which will appear as the description proceeds, my invention resides in the combination and arrangement of parts hereinafter described and set forth in the claims.

In the accompanying drawings wherein I have shown a convenient embodiment of 70 my invention,

Fig. 1 is a vertical section through a dobby having my invention applied thereto,

Fig. 2 is a fragmentary top plan view taken in the direction of arrow 2, Fig. 1,

Fig. 3 is a vertical section on line 3—3 of Fig. 1,

Fig. 4 is a side elevation of one of the fingers, preferably one which cooperates with the lower hooks,

Fig. 5 is a view of the other style of dobby finger which cooperates with the upper hooks,

Fig. 6 is a detail operating view showing the fingers held in raised position by the 85 levelling device,

Fig. 7 is an enlarged horizontal section on line 7—7 of Fig. 1,

Fig. 8 is perspective view of the levelling device, and

Fig. 9 is an enlarged horizontal section on line 9—9 of Fig. 4.

Referring to the drawings, it will be seen that I have provided a harness jack 20 pivoted on a fixed pin 21 and having pivotal connection as at 22 with a dobby back lever 23. The upper end of said lever 23 is pivoted to a hook 24 which cooperates with a horizontally reciprocating knife 25 while the lower end of said lever is pivotally connected with hook 26 which cooperates with another reciprocating knife bar 27 which always moves in a direction opposite to that of knife 25. Fixed stop bars 28 position the lever 23 and other bars 29 may be positioned to support the hooks and serve as guides for the lifting wires to be described hereinafter. There will be several jacks and levers, de-

pending upon the number of harness frames in the loom.

The pattern mechanism comprises a cylinder 30 movable on a shaft 31 and cooperating with chain bars 32 having pegs 33 to present the latter to indicating position, either each pick of the loom if the dobby be of the so-called single index type or every second pick of the loom, if the dobby be double index.

10 The dotted frame *d* has secured thereto a bar preferably made of wood and indicated at 34, held in place by means of bolts 35 which pass through the bar and also through the foot 36 of an open bearing 37 so formed as to have a substantially semi-circular opening 38 which is closed by the lower outer edge of bar 34. It is to be understood that the bar 34 extends for the full width of the dobby and that there are two 20 open bearings 37.

The levelling device L is formed substantially as shown in Fig. 8 with bearing portions 39, one of which is received by each of the openings 38. Said levelling device 25 is provided with one or more handles 40 by means of which the same may be turned from the position shown in Fig. 1 to the position shown in Fig. 6. The levelling device shown herein is merely illustrative and 30 I do not wish to be limited to the particular form shown.

In carrying out my present improvements, I provide two distinct types of dobby fingers which cooperate with a special form of 25 comb. The type of finger 50 shown in Fig. 5 has a substantially straight inwardly extending tail 51 on which rests lifting rod 52, there being one rod for each of the upper hooks 24. The opposite end of finger 50 40 is enlarged as at 53 to add weight as is usual with dobby fingers. The type 54 shown in Fig. 4 has an upwardly curved tail 55 on which rests one or another of the lower hooks 26. The opposite end of said 45 finger 54 is also enlarged as at 56 but said enlargement is further provided with a vertical slot 57 for a purpose to be described. The fingers of both types are provided with 50 supporting notches 58 which receive a rod 59 and there may further be provided a wire 60 extending above the rod 59 to prevent 55 improper upward displacement of the fingers.

The bar 34 is provided with relatively 55 short upwardly extending pins 61, so proportioned as to lie within the vertical slots 57. There will be as many pins 61 as there 60 are fingers 54, and by referring to Fig. 7 it will be seen that fingers 54 alternate with fingers 50, so that a pin or wire 61 will lie between fingers of the type indicated at 50. The diameter of the wires 61 may be slightly more than the thickness of fingers 54.

65 By referring to Fig. 1 it will be seen that

the right hand ends of all the fingers extend beyond the bar 34 so as to be operatively positioned with respect to levelling device L. The under sides of both types may be concaved to form runs 62 (see Fig. 70 3) to receive the pegs 33 of the pattern mechanism. The runs are formed by flaring outwardly the lower edges of the fingers, and in order to prevent these widened portions from interfering with each other, and 75 also to properly space the fingers of the type shown in Fig. 4, I form the latter as shown in Figs. 7 and 9. As set forth more particularly in Fig. 9 each finger 54 has a double offset, the first indicated at 63 extending slightly to one side of the finger while the second offset 64 extends an equal amount on the other side of the finger. Said offsets engage the parts 53 of the neighboring fingers 50 to guide the fingers 80 85 54 and to prevent interference of the adjacent runs 62.

The pins 61 serve to position the dobby hooks 50 and the latter in turn position fingers 54. In a double index dobby there 90 will be an even number of fingers, one half of each type, and there will therefore be a finger on one end of the set with the slot 57. In order to restrain improper lateral movement of such finger, the end peg or 95 wire adjacent the slot 57 of the last finger 54 is made somewhat longer than the others as indicated at 65 in Fig. 6.

From the foregoing it will be seen that I have provided dobby fingers the ends of 100 which are of substantially uniform thickness and that they are made in two types, one of which is formed to receive the guide for the other type. It will also be seen that all the fingers are so positioned and formed 105 as to be in operative relationship with the levelling device L. Furthermore, the heavier finger 50 will lift the wire 52 as well as one of the hooks, whereas the relatively lighter finger 54 will be called upon to lift 110 the hook only. Also, the fingers are formed with concaved flared runs and one type of finger is formed with offset parts which serve to position the fingers of that type. Furthermore there is a peg of extra length 115 provided to prevent lateral displacement of the end finger of the type shown in Fig. 4.

Having thus described my invention it will be apparent that changes and modifications may be made therein by those skilled 120 in the art without departing from the spirit and scope of the invention, and I do not wish to be limited to the details herein disclosed but what I claim is:

1. In a loom dobby having pattern 125 mechanism and harness actuating elements, a set of fingers movable about a common center and operatively positioned with respect to the pattern mechanism and operatively connected to the elements, and guid- 130

ing members interposed between certain of the fingers and located in openings extending through certain other fingers so that said guiding members are in substantial alignment with said certain other of the fingers, all of the fingers being of substantially the same length.

2. In a loom dobby having pattern mechanism and harness actuating elements, a set of dobby fingers to cooperate with the pattern mechanism, a levelling device for the fingers, and guide members for certain of the fingers located in openings extending through other of the fingers and in alignment with said other fingers, all of said fingers projecting beyond the guide members to be operatively positioned with respect to the levelling device.

3. In a loom dobby having pattern mechanism and harness actuating elements, a set of dobby fingers, a pivotal support for all the fingers adjacent to one end of the fingers, a levelling device for all the fingers adjacent to the other end of said fingers, and guide members for certain of the fingers located between the pivotal support and levelling device and located in openings extending through certain other fingers so that said guiding members are in substantial alignment with said other fingers, all of said fingers extending beyond the guide members to be operatively positioned relatively to the levelling device.

4. In a loom dobby having pattern mechanism and harness actuating elements, a set of fingers movable about a common center and for the pattern mechanism operatively connected to the elements, and fixed separating members located between alternate fingers and located in openings extending through the intervening fingers, the intervening fingers being projected beyond the separating members so that all of said fingers are of substantially the same length.

5. In a loom dobby having pattern mechanism and harness actuating elements, a set of dobby fingers for the pattern mechanism operatively connected to the elements, and spaced guide members received by openings extending through certain of said members, said fingers formed with openings for the members also being extended beyond the members so that all of said fingers are of substantially the same length.

6. In a loom dobby having pattern mechanism and harness actuating elements, a set of dobby fingers for the pattern mechanism operatively connected to the elements, spaced guide members received by openings extending through certain of said fingers, other fingers extending beyond and being guided by said members, said fingers formed with openings for the members also being extended beyond the members so that all of said fingers are of substantially the same

length, and a levelling device to be moved into engagement with all of the fingers to have operative contact with the latter at points between the adjacent ends of the fingers and the members.

7. In a loom dobby having pattern mechanism and harness actuating elements, a set of dobby fingers to cooperate with the pattern mechanism operatively related to the elements, guide members, certain of the fingers being formed with slots in their under sides to receive the members, the other fingers being guided by the members and all of said fingers having portions extending above the members, whereby the members will guide said other fingers and the latter will guide the slotted members and all of said fingers will be mutually guided by each other by reason of the portions thereof which extend above the members.

8. In a loom dobby having pattern mechanism, an upper set of hooks, a lower set of hooks, lifting rods for the upper set of hooks, and a set of fingers operatively related to the pattern mechanism, spaced guide members to separate the fingers, certain of said fingers having slots extending therethrough to receive the guide members and having direct engagement with the lower set of hooks, the other fingers being guided by and extending between the members and having operative engagement with the lifting rods for the upper set of hooks.

9. In a loom dobby having pattern mechanism, an upper set of hooks, a lower set of hooks, lifting rods for the upper set of hooks, and a set of fingers operatively related to the pattern mechanism, spaced guide members to separate the fingers, certain of said fingers having slots extending therethrough to receive the guide members and having direct engagement with the lower set of hooks, the other fingers being guided by the members and having operative engagement with the lifting rods for the upper set of hooks, and a pivotal support for all said fingers located between the pattern mechanism and that portion of the fingers which moves to raise the hooks.

10. A dobby finger for a loom dobby having a separating comb and having two dobby fingers spaced by the comb and restrained against lateral movement by the comb, said finger to lie between the said two fingers and having an opening extending therethrough to receive that part of the comb which spaces said fingers and having another portion thereof offset to engage and be guided by one of said two fingers.

11. A dobby finger for a loom dobby having a separating comb and having two dobby fingers spaced by the comb and restrained against lateral movement by the comb, said finger to lie between the said two fingers and having an opening extending

therethrough to receive that part of the comb which spaces said fingers and having another portion thereof offset on both sides of said dobby finger to engage and be guided by said two fingers.

12. A dobby finger for a loom dobby having a separating comb and a pattern mechanism, said finger having a run on the bottom edge thereof for the pattern mechanism formed by flaring a portion of the lower edges of the finger, other parts of the finger being removed to receive a part of the comb and still other portions of the finger being offset out of the plane of the finger to cooperate with adjacent fingers and act as a guide.

13. In a loom dobby, a set of dobby fingers certain fingers having substantially plane vertical walls and certain other fingers having offset portions projecting beyond the surfaces thereof to engage the plane surfaces of the first named fingers to space the fingers.

14. In a loom dobby, a set of dobby fingers certain fingers having substantially plane vertical walls and certain other fingers hav-

ing offset portions projecting beyond the surfaces thereof to engage the plane surfaces of the first named fingers to space the fingers, and a peg run on the under side of each of the fingers formed by having a portion of the lower edge of the fingers extend laterally beyond the plane vertical surfaces of the fingers.

15. In a loom dobby, a set of dobby fingers, a separating comb having a plurality of spaced separating members for the fingers, alternate fingers having portions thereof removed to receive the separating members of the comb and the intermediate fingers having portions thereof to engage the members, said fingers being arranged in pairs so that the end finger at one side of the set is provided with an opening, and an additional member forming a part of the comb to engage and restrain lateral movement of the said end finger.

In testimony whereof I have hereunto affixed my signature.

ELBRIDGE R. HOLMES.
